UNITED STATES PATENT OFFICE

104,387

DESIGN FOR A HOLDER FOR LABELS OR THE LIKE

Egmont H. Arens, New York, N. Y., assignor to
The Hobart Manufacturing Company, Troy,
Ohio, a corporation of Ohio

Application February 13, 1935, Serial No. 55,394

Term of patent 14 years

To all whom it may concern:

Be it known that I, Egmont H. Arens, a citizen of the United States of America, residing at New York, in the county of New York, State of New York, have invented a new, original, and ornamental Design for a Holder for Labels or the like, of which the following is a specification, reference being had to the accompanying drawing, forming a part thereof, in which

Fig. 1 is a front elevational view of a holder for labels showing my new design; and

Fig. 2 is an edge view thereof.

The design is for a holder adapted to be attached to the side of a food handling device such as a coffee mill for holding a label for instructions or the like.

I claim:

The ornamental design for a holder for labels or the like substantially as shown and described.

EGMONT H. ARENS.
